UNITED STATES PATENT OFFICE.

GEORGE ALFRED FORD, OF KANSAS CITY, MISSOURI.

TYING DEVICE.

1,387,699.

Specification of Letters Patent. Patented Aug. 16, 1921.

Application filed November 10, 1919. Serial No. 337,097.

To all whom it may concern:

Be it known that I, GEORGE ALFRED FORD, a citizen of the United States, residing in Kansas City, county of Jackson, and State of Missouri, have invented a certain new and useful Improvement in Tying Devices, of which the following is a specification.

My invention relates to tying devices for packages and particularly to tying devices adapted for use by the Post Office Department for tying up packages of letters. Objects of my invention are to provide for the quick tying and untying of the package and to provide a light and inexpensive tying device which can be reused over and over again, together with other objects and advantages which will hereinafter appear.

I shall now describe the tying device embodying my invention shown in the accompanying drawings and shall thereafter point out my invention in claims.

Figure 1 is a plan view of a package of letters tied up with a tying device embodying my invention.

Fig. 2 is an elevation as viewed from the right in Fig. 1.

Fig. 3 is a view similar to Fig. 1 but illustrates an intermediate stage of the tying operation.

Fig. 4 is an enlarged central longitudinal section of the tying device with a part of the tie string omitted.

Fig. 5 is a similarly enlarged plan view with the tie string omitted.

Fig. 6 is a vertical transverse section on a plane indicated by the line 6-6 of Figs. 4 and 5 as viewed from the left and as seen in Fig. 4.

In the embodiment of the invention shown in the drawings, a sheet metal base 1 has semicircularly rounded ends and straight side edges. The marginal edges of the base plate 1 are turned downward all around and are disposed in the same plane and are adapted to come into contact with the surface of a package, so as to have a gripping relation thereon. An outwardly indented annular bead 2 is provided contiguous to and coterminous with one end of the base plate

1, the flat surface of the plate 1 within this upraised annular bead 2 being adapted to receive the thumb of the left hand of the operator. A fairly good sized aperture 3 is provided in the base 1 centrally of the annular bead 2, the edges of this aperture 3 serving to grip the thumb of the operator

which is permitted to come into contact with the underlying package through this aperture. The bead 2 and aperture 3 together provide for the thumb firmly holding the device in place and obviate both the slipping of the base plate from beneath the thumb or the slipping of the thumb from off the base plate.

At the other end of the base plate 1 there is provided an elevation or platform forming a button-carrying pedestal 4 which rises in a rounded curve from the base plate 1 and is contiguous to and coterminous with the sides and end of the base plate 1, this button-carrying pedestal 4 being indented outwardly in the sheet metal base plate 1. The top of this button-carrying pedestal 4 is shown as flat, excepting at the center thereof there is provided a further elevated part or neck 5 which is indented outwardly from the platform 4. A sheet metal string-holding button 6 is convex on its lower side so as to be substantially of saucer shape and is firmly secured by means of a tubular rivet 7 upon the top of the neck 5.

Upwardly indented straight beads or ribs 8 extend along the side edges of the base plate 1 and merge into and join the annular thumb-retaining bead 2 and the rounded edge of the elevated button-carrying platform or pedestal 4. The annular bead 2, the button-carrying elevation or pedestal 4, and the straight side ribs or beads 8 coöperate to provide the downwardly turned gripping edges on the base plate 1, hereinbefore mentioned. The side ribs or beads 8 are shown as of the same height or elevation as the annular bead 2 while the flat top part of the button-carrying platform or pedestal 4 is at a somewhat greater height. A tie string 9 is knotted at one end and passes downward through the tubular rivet or eyelet 7 and is adapted, in the tying operation, to be wound about a package and secured by means of the string-holding button 6. In the drawings the tying device of my invention is shown as made use of to tie up a package of letters 10 upon which a usual destination slip 11 has been placed.

In the tying operation the device is placed centrally upon a package of letters at an angle of about forty-five degrees, as shown in Fig. 3, and is firmly held in place by the thumb of the left hand pressing within the space inclosed by the annular bead 2. The string 9 is then wound forwardly over and

around the package lengthwise and a three-quarter turn thereof is taken around the button 6 in a clockwise direction, as shown in Fig. 3 and as is indicated by the arrow 5 on the button 6, the string of course being pulled taut before it is carried around the button. Next the string 9 is wound transversely around the package in a clockwise direction as viewed from above in Fig. 1, and 10 as is indicated in Fig. 3. The string is then pulled taut and is given about one turn around the string-holding button 6, thereby completing the tying operation, as shown in Figs. 1 and 2. Should the package of 15 letters be small, any surplus string may be wound around the package and then fastened by a final winding about the button 6; or, if preferred, the string may be wound initially several times around the package 20 without winding about the button, and then the end fastened by winding about the button. After the tying is completed and the thumb is removed, the tension on the taut string 9 will twist the base plate 1 around 25 from the initial oblique position thereof shown in Fig. 3 to substantially the longitudinal position thereof shown in Figs. 1 and 2. For untying a package the tying operation is substantially reversed.

30 The following more important advantages may be noted as resulting from the hereinbefore described construction. The base plate 1 rests flatly upon the package of letters and the downturned edges thereof grip 35 and have a firm hold on the package, preventing slipping in the tying operation. The rounded marginal surfaces produced by the downturned gripping edges preclude any 40 possibility of injury to the hand in the tying operation. The raised position of the string-holding button 6, on the platform or pedestal 4 greatly facilitates the tying operation, providing for easily and quickly winding the string about the string-holding button 45 6. The fact that the winding of the string around the package and also around the button may be always in the same clockwise direction, is a convenience which shortens the time of the tying operation, no reversal 50 of movement of the hand being required. During the winding and string-fastening operation the thumb of the left hand which holds the base plate 1 in place is entirely out of the way, as will be apparent from an 55 inspection of Fig. 3, so that the string will not be wound over the thumb nor will the thumb obstruct the winding of the string around the string-holding button.

It is obvious that various modifications 60 may be made in the construction shown in

the drawings and above particularly described within the principle and scope of my invention.

I claim:

1. A tying device comprising an elongated base plate having downwardly projecting portions adapted to lie upon the package being tied to hold the device against twisting, and having at one end thereof an elevated part forming a button-carrying pedestal, 65 and a string-holding button carried upon the top of said pedestal.
2. A tying device comprising an elongated base plate having downwardly projecting portions adapted to lie upon the package being tied to hold the device against twisting and other projections forming at one end a thumb hold and having at the other end thereof an outwardly indented part forming a button-carrying pedestal, and a string-holding button carried upon the top of said pedestal. 75
3. A tying device comprising an elongated base plate having its ends rounded and its edges all around turned downward and disposed in the same plane so as to rest in gripping relation upon a package to hold the device against twisting during the tying of the package, said turned down edges being formed in part at one end by an annular 80 bead providing for the reception and retention of the thumb within the bead, said turned down edges being formed in part at the other end by a button-carrying elevation on the base plate, and said turned down 85 edges intermediate the ends of said base plate being formed by means of marginal beads uniting the said annular bead at one end of the base plate with the marginal part of said button-carrying elevation, and a 90 string-holding button carried by said button-carrying elevation. 95
4. A tying device comprising an elongated base plate provided adjacent to one end thereof with a thumb-gripping and thumb-retaining aperture, a string-holding button carried by the base plate on its upper side adjacent to the other end thereof, and a tie string secured at one of its ends to the button-carrying end of the base plate and adapted to be wound about the package and secured by means of said button, and gripping projections projecting from the bottom adapted to lie flat upon the package and hold the device against twisting during tying of 100 the package. 105

In testimony whereof, I have affixed my signature to this specification.

GEORGE ALFRED FORD.
